(57) CLAIM

The ornamental design for a cooking grate, as shown and described.

DESCRIPTION

FIG. 1 is front elevational view, the rear elevation view being identical thereto.

FIG. 2 is a top plan view.

FIG. 3 is a right side elevational view, the left side elevational view being identical thereto.

FIG. 4 is a bottom plan view; and,

FIG. 5 is a perspective view, showing the front, right side, and top.

The broken lines are included for the purpose of illustrating portions of the cooking grate that forms no part of the claimed design.
